(57) **CLAIM**

The ornamental design for a “tire”, as shown and described.

DESCRIPTION

FIG. 1 shows a perspective view of a tire showing my new design, it being understood that the design repeats uniformly throughout the circumference of the tire, as depicted schematically in solid lines in FIGS. 1-4;

FIG. 2 shows a right elevational view of the present design.

FIG. 3 shows a front elevational view of the present design; and,

FIG. 4 is an enlarged plan view showing a section of the tread of the present design.
